C. AUGENSTEIN ET AL

CHAIN

Filed Dec. 9, 1926

UNITED STATES PATENT OFFICE.

CARL AUGENSTEIN, OF CRANSTON, AND ROBERT VOGEL, OF PROVIDENCE, RHODE ISLAND, ASSIGNEES TO AUTOMATIC GOLD CHAIN COMPANY, A FIRM COMPOSED OF EDWIN F. M. SPEIDEL AND ALBERT R. SPEIDEL, BOTH OF EDGEWOOD, RHODE ISLAND.

CHAIN.

Application filed December 9, 1926. Serial No. 153,528.

This invention relates to an improved construction of chain or bracelet formed of a plurality of extendible links; and the object of this invention is to construct such a chain or bracelet having outer or guide links formed of sheet stock folded to the desired shape and an inner slide link provided with a hook-shaped portion by which it may be readily connected to and disconnected from the next adjacent link of the chain or bracelet.

A still further object of the invention is to fold the stock of the guide link so as to provide a broad-front wall, side walls and portions of the rear wall with a longitudinal opening therein, the rear wall portions being provided with inwardly-extending abutments against which one end of the operating spring acts for the purpose of pressing the slide link toward contracted position in its guide link.

A still further object of the invention is the provision of a slide link formed of elongated band shape and having one relatively broad arm of a width to be guided between the side walls of its guide link, one end of this broad arm being turned up to form a hook, and this slide link being also provided with a relatively narrow resilient arm arranged to slide in the space formed in the rear wall of the guide link to close the same and complete the broad bearing rear wall, the free end of this narrow arm engaging the under side of the hook to prevent it from opening outwardly, a single spring being mounted in each link unit of a width to be guided by the side walls of the guide link and engage both of the abutment lips which extend inwardly from the rear walls of this guide link.

With these and other objects in view, the invention consists of certain novel features of construction, as will be more fully described, and particularly pointed out in the appended claims.

In the accompanying drawings:

Figure 1 is a perspective view showing a series of links of our improved form connected together.

Figure 2 is a perspective view of the under side of one of the guide links showing the

longitudinal space therein and the abutment fingers in extended position on the rear wall portions thereof.

Figure 3 is a bottom view of this guide link.

Figure 4 is a section on line 4—4 of Figure 3.

Figure 5 is a perspective view of the slide link showing the narrow arm of the band as extending beneath the hook-shaped portion formed on the broad arm of the band.

Figure 6 is a bottom view of this slide link.

Figure 7 is an edge elevation of this slide link.

Figure 8 is a sectional view showing a plurality of slide links in partially extended position in the guide links.

Figure 9 is a sectional edge view showing the links of the chain in the same relative position as illustrated in Figure 8.

Figure 10 is a sectional end view on line 10—10 of Figure 9.

Figure 11 shows the hook of the slide link with its tongue depressed to engage the cross bar on the next adjacent guide link.

It is found of advantage in the construction of bracelets of this character, to provide a guide link of sheet stock, the blank of which is folded to form a broad, front face with narrow edge walls and having inwardly extended rear wall portions, the edges of which are spaced apart to provide a longitudinally-disposed guide slot therein and to provide an elongated band-shaped slide member the front arm of the band being formed of a relatively broad plate to be guided between the side walls of the guide link, and having a hook formed adjacent one end thereof, also to provide the rear arm of this band somewhat narrower to fit into the longitudinal channel or space in the rear wall of the guide link to close this space.

This arm also being arranged to extend forwardly beneath the hook formed on the broad arm to prevent the arm from opening outwardly, this construction of link unit permitting a broad coiled spring to be inserted therein and extend through the opening between the arms of the slide link and so serve to be guided between the walls of

the guide link and also to prevent the opening or depressing of the resilient arm of the hook except when the link members are in extended position and the following is a detailed description of the present embodiment of our invention and showing one means by which these advantageous results may be accomplished:

With reference to the drawings, 10 designates the guide link the blank of which is formed from sheet stock and subsequently folded to provide a broad front wall 11 for the reception of suitable ornamentation, portions of which front plate are bent back 15 providing relatively narrow side walls 12 and portion of these side walls are turned inwardly toward each other leaving a longitudinally-disposed central space 13 between them. The edges of these side walls 20 at one end of the link are preferably connected by an integral bar 14 and at the opposite end the rear wall portions 15 are provided with fingers 16 which are adapted to be bent inwardly to provide a pair of abutments for one end of the single spring presently described.

Another element in this link is a slide link member 17 which is preferably formed in an elongated band shape, the front arm 18 of which is of a width to slide between the edge walls 12, of the guide link as best shown in Figure 10. One end of this broad arm or plate is turned up as at 19 into hook form, the opposite arm 20 of this band-shaped link being resilient and is considerably narrower than the front arm 18 thereof. This rear arm being of a width to fill the longitudinal space 13 in the rear wall of the guide link and is preferably set flush with these rear 40 wall portions 15 to complete the full bearing surface of the bracelet link unit on the arm of the wearer, the forward end 21 of this arm 20 is arranged to extend under the edge 23 of the hook to prevent it from opening outwardly and this arm is prevented from being opened inwardly by a spring 24 except when in extended position as this spring 24 extends across the link beneath this arm 20 and is guided by and between the side walls 50 of the slide link.

In assembling the parts the slide link is positioned in the guide link by simply sliding one within the other, the single spring 24 is inserted with one end 25 engaging the band 26 of the slide link, then the outer end of the spring is compressed and the fingers 16 on the end of the rear wall portions are turned inwardly and serve as abutments for the adjacent end of the spring to hold it by 60 compression and cause it to press the slide link towards closed position. After these link units have been assembled it is only necessary to extend the slide member of the unit in its guide link sufficiently beyond the end 65 of the spring 24 in order to permit this arm

or tongue 20 to be depressed sufficiently to be hooked into the end bar 14 on the adjacent end of the next guide link 12.

Our improved bracelet or chain is very simple and practical in construction and the unit parts may be readily assembled and be detachably connected one with the other by simply extending the slide link in its guide link and passing its hook end through the bar 14 on the end of the next adjacent slide link whereby a chain or bracelet may be assembled of any desired working length.

The foregoing description is directed solely towards the construction illustrated, but I desire it to be understood that I reserve the privilege of resorting to all the mechanical changes to which the device is susceptible, the invention being defined and limited only by the terms of the appended claims.

We claim:

1. A bracelet structure comprising a series of extendible link units, each having a guide link formed of sheet stock folded to provide a front wall, side walls and portions of a rear wall said portions being spaced apart, an elongated band-shaped slide link in said guide link having a hook portion and having a broad arm member guided between the edge walls of the guide link and a narrow arm lying between and flush with said rear wall portions of said guide link, a spring guided between the side walls of the guide link and having one end acting on the fold of the band slide link, and inturned fingers on each rear wall portion of the guide link serving as spaced abutments for the opposite end of said spring.

2. In an extendible bracelet chain, a series of guide links folded from sheet stock to form front, side and portions of a rear wall, the edges at the rear wall being spaced to provide a longitudinal slot therethrough, an elongated band slide link in said guide link having a hook portion adjacent one end and having a broad arm member guided between the side walls of the guide link, and a narrow arm lying flush with and slidably in the space in said rear wall and adapted to be sprung inwardly to open the hook portion, spring abutment members carried by said guide link and a spring acting between said abutment members and the slide link to press the latter towards housed position, and a member at one end of the guide link with which the hook of the next adjacent slide link may be engaged to detachably connect the link elements together.

3. In an extendible bracelet chain, a series of guide links folded from sheet stock to form front, side and portions of a rear wall, the edges at the rear being spaced to provide a longitudinal slot therethrough, an elongated band-shaped slide link in said guide link having a hook portion adjacent

one end and having a broad arm member guided between the side walls of the guide link and a narrow arm lying flush with and slidable in the space in said rear wall and adapted to be sprung inwardly to open the hook portion, a spring acting to contract the guide link and the slide link and positioned beneath said narrow resilient arm to prevent the resilient arm from being depressed and the hook opened except when in extended position and a member at one end of the guide link to which the hook of the adjacent slide link may be detachably connected.

4. A bracelet structure comprising a series of extendible link units, each having a guide link formed of sheet stock folded to provide

a front wall, side walls and portions of a rear wall, said portions being spaced apart, a band-shaped slide link in said guide link 20 having a hook portion and having a broad arm member guided between the edge walls of the guide link and a narrow arm lying between and flush with said rear wall portions of the guide link, a spring having one 25 end acting on the fold of the band-shaped slide link, and inturned fingers extending from one of the walls of the guide link at one end thereof serving as abutments for the opposite end of said spring. 30

In testimony whereof we affix our signatures.

CARL AUGENSTEIN.
ROBERT VOGEL.
